UNITED STATES PATENT OFFICE.

PAUL DOANE, OF KANSAS CITY, MISSOURI.

BILLIARD-CUE.

1,182,530.

Specification of Letters Patent. Patented May 9, 1916.

Application filed March 20, 1915. Serial No. 15,882.

To all whom it may concern:

Be it known that I, PAUL DOANE, a citizen of the United States, residing at Kansas City, in the county of Jackson and State 5 of Missouri, have invented certain new and useful Improvements in Billiard-Cues; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to billiard cues, and has for its principal object to provide a cue with hammer mechanism whereby a blow may be struck to drive the ball without moving the cue after it has been properly located for directing a shot.

20 In accomplishing this object I have provided the details of structure hereinafter described, the preferred forms of which are illustrated in the accompanying drawings, 25 wherein:

Figure I is an elevation of a billiard cue constructed according to my invention. Fig. II is an enlarged longitudinal section of a part of the same. Fig. III is a cross section on the line III—III, Fig. II. Fig. 30 IV is a further enlarged longitudinal section of the trigger mechanism and butt of the cue.

35 Referring more in detail to the parts:—1 designates the body of the cue, which comprises a metal tube having one end closed by a cap 2 and its opposite end reduced by a bottle neck 3, so that it terminates in a tubular section 4 of less diameter than the 40 body 1; the outer end of the reduced section 4 having a closed, rounded tip 5 of substantially the same shape and size as the tip of an ordinary billiard cue.

45 Located at intervals throughout the length of the cue and fixed therein are bearing blocks 7, which serve to stiffen the tubular members and have central registering bores 8 for carrying the plunger rod 9 and hammer rod 10. The plunger rod 9 is located within the outer reduced member 4 and carries, at its outer end, a head 11, the 50 face 12 of which is curved like an ordinary billiard cue tip and the sides of which are tapered so that they fit snugly within a 55 tapered seat 14 in the cue tip 5, the inner end of the head having a shoulder 15 adapt-

ed to abut against the end of the outer bearing block 7 to limit the inward travel of its plunger rod.

The plunger head and rod are yieldingly 60 retained in initial position by a spring 17 which is fixed to the plunger rod and to one of the blocks 7, so that the head 11 is normally in its seat but may be projected to strike a ball when the plunger is actuated by 65 the hammer rod 10. The inner end of the plunger rod has a head 19 formed thereon against which the hammer head 20 of the rod 10 is adapted to strike; the said hammer rod being also provided with a spring 21, 73 which is fixed to one of the blocks 7 and to the rod and arranged to yieldingly urge the rod forwardly so that the hammer rod will strike the plunger head 19 when the hammer rod is released, as presently described; the arrangement of the hammer rod and spring 21 being such that the head 20 is normally retained out of contact with the plunger head 19, so that after the actuating blow is struck the spring 21 will return 75 80 to initial position and thereby effect a blow corresponding to the blow that is struck with an ordinary cue.

Pivotaly mounted in the body of the cue, near the butt end, is a trigger 23 having a 85 finger piece 24 projected through a slot 25 in the body of the cue and protected by a guard 25', the inner end of the trigger having a tooth 26 adapted for engagement with one of the ratchet teeth 27 in the hammer rod. 90 The trigger is yieldingly retained in its rod-engaging position by a spring 28 so that when the trigger is free its tooth will engage the hammer rod.

Slidably mounted on the body of the cue 95 is a collar 29 having a bar 30 fixed thereto and slidably projected through slots 31 in the cue body so that it may move longitudinally therethrough; the center of the bar being provided with an aperture 32 through 100 which the plunger rod is projected, and the diameter of the aperture being such that the rod may move freely therein.

105 Fixed to the hammer rod is a pin 34 which is adapted for engagement by the cross bar 32 so that when the sleeve is moved backwardly over the cue body, the bar will engage the pin and move the hammer rod back against the tension of its spring so that the trigger may engage the ratchet teeth to cock 110 the hammer.

I prefer to provide a cushion 35 in the butt

of the cue against which the butt of the hammer rod may strike when it reaches its rearward position and thereby relieve the sleeve bar from the strain which would occur if it struck the base of the slot 31.

In using the device, presuming the parts to be constructed and assembled as described, when the player is about to make a shot, he moves the sleeve 29 back to tension the spring 21 and cock the hammer. The player then positions the cue in the ordinary manner and when the shot is to be made he releases the hammer rod by means of the trigger so that the spring throws the hammer forwardly to impact the plunger. The blow of the hammer against the plunger drives the latter forwardly to contact the ball and effect the shot. As the hammer strikes the plunger a sharp blow, but does not follow the plunger, the latter is free to move back under tension of its spring, so that a shot much resembling the ordinary

draw shot is effected. The hammer may then be reset by pushing inwardly on the end of the plunger.

Having thus described my invention, what I claim as new therein and desire to secure by Letters-Patent, is:

A billiard cue comprising a plunger having an exterior tip, yielding means for returning the plunger to normal position, a hammer adapted for striking the plunger, yielding means for effecting the hammer blow, a trigger mechanism for holding the hammer against its yielding means, and a collar slidably mounted on the cue, and means on said collar for engaging the hammer to set the same.

In testimony whereof I affix my signature in presence of two witnesses.

PAUL DOANE.
